UNITED STATES PATENT OFFICE.

OTTO W. SCHAUM, OF PHILADELPHIA, PENNSYLVANIA.

BALL-GRINDING MACHINE.

1,232,245.

Specification of Letters Patent. Patented Jan. 1, 1918.

Application filed March 24, 1917. Serial No. 157,245.

To all whom it may concern:

Be it known that I, OTTO W. SCHAUM, a citizen of the United States, and a resident of Philadelphia, county of Philadelphia, State of Pennsylvania, have invented new and useful Improvements in Ball-Grinding Machines, of which the following is a specification.

The invention relates to ball grinding machines and particularly to machines of the type in which balls while being ground by means of an abrading wheel are supported by or rest upon spaced rings against which the balls are pressed by means of a rotating ball-revolving ring.

In machines of this type that portion of the ball which is to be operated upon is forced through the space between said rings by the ball-revolving ring and is acted upon by the abrading wheel which is on the opposite side of the spaced supporting rings from that upon which the ball revolving ring is located.

According to the preferred embodiment of the present invention these spaced supporting rings are supported on a common carrier. When the carrier—be it a one piece member or a built up construction—for said spaced rings is moved toward the abrading wheel both of said rings will also be moved toward the abrading wheel. The ball revolving ring is on a revolving carrier. The common carrier above referred to comprises an inner carrier or arbor and an outer carrier, preferably integral with each other. There is also mounted upon the common carrier—preferably upon the inner carrier or arbor—the revolving carrier for the ball-revolving ring. This revolving carrier or intermediate carrier as it may be called is adjustable along the inner carrier or arbor so as to control the pressing of the balls being ground against the spaced supporting rings. The intermediate carrier being mounted on the common carrier results in a construction in which the ball revolving ring, and the spaced supporting rings can be simultaneously positioned toward or from the abrading wheel by a movement of the common carrier.

The construction which is the basis of the present invention is particularly adaptable for employment in a double grinding ma-

chine, to wit, in a grinding machine in which similar grinding operations can be performed at opposite ends of a machine by abrading wheels on a common shaft.

The invention is directed to the features above referred to and also to other features of construction which will be hereinafter pointed out.

As showing a specific embodiment of the invention reference is made to the drawings forming a part of this specification and in which drawings,

Figure 1 is a side elevation, partially in section, of a double grinding machine.

Fig. 2 is an end elevation, partially in section, of the machine shown in Fig. 1.

Figs. 3 and 4 are respectively partial plan and partial sectional elevations of a dutchman construction which is employed between a supporting ring and its carrier.

Fig. 5 is a view taken as on the plane indicated by the line 5—5 of Fig. 1 looking in the direction of the arrows.

The main frame of the machine is designated by 1 and upon the central portion thereof there is mounted any suitable housing, as 2. At each end of this housing 2 there is provided suitable bearings, as 3. In these bearings there is rotatably mounted a shaft 4 having at each end thereof a head 5 to which there is secured through the medium of bolts 6 a tubular wheel of abrading material, to wit, an emery wheel 7 which is carried in a ring 8 into which the bolts 6 extend. The bearings 3 each preferably comprises an anti-friction radial bearing 9 and an anti-friction thrust bearing 10. These bearings 9 and 10 are shown as ball bearings. The shaft 4 may be driven by any suitable source of power but it is preferably driven by means of an armature thereupon, which armature is a part of an electric motor the field of which motor is within the housing 2. As the construction of such a motor is old and well known in the art the details thereof are not shown and described herein.

An inner ring 11 and an outer ring 12 are provided opposite the operative face of each abrading wheel. The rings 11 and 12 are spaced apart and are the spaced supporting rings. These rings are frequently referred to as segment rings, this because the por-

tions thereof which are engaged by the balls being ground are made of segments which, when assembled, constitute a complete ring. The rings 11 and 12 may also be referred to 5 as guiding rings since they perform the function of guiding the balls as well as of supporting the balls while the grinding operation is being performed. The series of balls, designated as 13, when being ground 10 press against seats which are on the rear sides of these rings and the balls are maintained in their proper position on the seats by means of the rotating ball-revolving ring 14. This ring 14 may also be referred 15 to as the ball-pressing ring. It presses against the balls with a sufficient force to maintain the balls firmly against the seats, it maintains the balls in operative engagement with the abrading wheel during the 20 grinding operation and it rolls the balls being ground along the seats whereby successive surfaces of the balls will be operated upon during the grinding operation.

The inner segment ring 11 is carried on 25 the forward end—the end which is nearest to the abrading wheel—of an inner carrier or arbor 15. The outer segment ring 12 is carried on the forward end of an outer carrier 16. The carriers 15 and 16 are integral 30 with each other and constitute a common carrying member for the inner and outer segment rings. An intermediate carrier 17 is mounted upon and so that it can revolve about the inner carrier or arbor 15. To this 35 intermediate carrier 17 there is secured, as will hereinafter appear, the ball-revolving ring 14. The intermediate carrier 17 instead of being directly mounted upon the inner carrier 15 is indirectly mounted there- 40 upon through the medium of a radial roller-bearing construction 18. There is also provided an adjusting mechanism 19 to position the intermediate carrier 17 along the inner carrier 15, or in other words to control the 45 pressing of the balls against the spaced supporting rings and relative to the abrading wheel. This adjusting mechanism comprises a gear 20 having interior screw-threads 21 which engage screw-threads 22 on the exte- 50 rior of the arbor 15, a spur-gear 23, a shaft 24, and a hand-operating wheel 25. The spur-gear 23 remains in place and is of a sufficient length to permit the gear 20 to move longitudinally along the inner carrier arbor 55 15 and at the same time to remain in operative engagement with the spur-gear 23 while being thus moved. Upon the exterior of the screw-threads 22 there slides a tubular bearing member 26 upon which there bear rolling 60 ers 27 of the roller-bearing construction 18. In other words, this tubular bearing member 26 provides the inner raceway of said roller-bearing construction 18. The outer raceway of this bearing is provided by a 65 tubular member 29 which is seated in a cut-

out or counter-bored portion of the intermediate carrier 17. Longitudinal thrust between the gear 20 and the rotatable intermediate carrier 17 is taken care of by means of a suitable thrust bearing which is 70 provided at 30. It will therefore be seen that the intermediate carrier 17 can rotate about the arbor 15, relative to the gear 20 of the feeding mechanism 19, and this rotation can take place while a feed or adjustment is being effected through the medium of the mechanism 19.

The ball-revolving ring or ball-pressing ring 14 is connected to or driven by the intermediate carrier 17 through the medium 80 of an annular ring 31 which slides upon pins 32 that are secured to an outwardly extending flange 33 of the intermediate carrier 17. Between the annular ring 31 and this flange 33 there are also provided compression springs 34 which constantly tend to force the annular ring 31 and pressing ring 14 away from the intermediate carrier 17; or, in other words, which tend to force the pressing ring 14 toward the abrading wheel 90 7. The distance which the springs can force the annular ring 31 away from the flange 33 is limited by the heads 35 of the pins 32.

A gear 36 is secured to the flange 33 by bolts 37 and this gear is driven from the motor M through the medium of a pinion 38, spur-gear 39 and pinion 40, the latter of which is a long gear that meshes with the gear 36. The pinion 40 is of sufficient length to always remain in engagement with the 100 gear 36 while the latter is being moved relative to the pinion 40 to its several adjusted positions. The pinion 40 is carried on a hollow shaft 41 that is plugged at 42 and which is provided with oil openings at 43. 105 The oil for lubricating purposes is supplied to the interior of this shaft through the medium of any suitable stem, as 44. The motor M and the gears driven thereby are all supported on the outer carrier 16 or in other 110 words upon the carrier which is common to the two spaced segment rings 11 and 12. Upon this carrier there is also mounted the feeding and mixing mechanism FM. This feeding and mixing mechanism is shown in 115 Fig. 2 and it will be observed that the balls pass from the grinding or working space between the abrading wheel 7 and pressing ring 14, roll along the path P defined by a discharge chute DC, into the flights F of an 120 endless conveyer EC from which they drop into another chute C and finally into a hopper H where the mixing is thoroughly effected. From this hopper the balls roll over a mixing cone MC into a flexible tube FT back 125 into the grinding space where another operation can be performed.

In order that the entire surface of the abrading wheel can be utilized the axis of the abrading wheel is offset or at one side 130

of the axis about which the ball-revolving ring or ball-pressing ring rotates. The location of the axis of the abrading wheel is designated in Fig. 2 as A E and the location 5 of the axis about which the ball-revolving ring or ball-pressing ring turns is designated as A P. The inner and outer supporting rings 11 and 12 are concentric with the ball-revolving or ball-pressing ring 14 and therefore eccentric relative to the axis of rotation of the abrading wheel.

From an inspection of Fig. 2 it will also be observed that in the operating of the machine each ball-revolving or ball-pressing 15 ring rotates in a direction opposite to that in which its corresponding abrading wheel rotates. As the abrading wheels are both mounted upon a common shaft, it will be observed that it becomes impracticable to move 20 the abrading wheels toward the work and for this reason the work and all the members which control its position are made so that they can be moved toward the abrading wheels as the abrading wheels wear away. 25 This movement of the several parts toward the abrading wheel is accomplished through the medium of mechanism K which comprises a hand-wheel 45, shaft 46, and nut 47 into which a threaded portion 48 of the shaft 30 extends. This nut 47 is on the common carrier of the segment rings 11 and 12. A bearing 49 is mounted on the main frame of the machine and this bearing is located between the hand-wheel 45 which is secured to the 35 shaft and a collar 50 that is also secured to the shaft. A mere turning of the hand-wheel in the proper direction will forcibly move not only the common carrier toward or from the abrading wheel, as desired, but 40 all the parts mounted thereupon, to wit, the inner and outer supporting or segment rings 11 and 12, the revoluble intermediate carrier 17 and ball-pressing ring 14 driven thereby, the motor M and gearing whereby 45 said motor can drive the intermediate carrier, the adjusting mechanism 19, the feeding and mixing mechanism FM and a motor M' for the latter. The motor M' is connected so that it can drive the mixing cone MC and 50 also the endless conveyer EC, as will be manifest from an inspection of Fig. 2.

The construction at one end of the double machine is a substantial duplicate of the construction at the other end of the machine. 55 In the normal operating of the machine work is fed to the abrading wheels and it will be observed that there is very little longitudinal thrust upon the thrust bearing 10 especially when the grinding operations are 60 being performed at each end of the machine. In other words the thrust in one direction of one abrading wheel is opposed by the thrust in a reverse direction of the other abrading wheel. Such being the case the 65 thrust bearings 10 can be comparatively

small and it will be observed they are small as when compared to the thrust bearings between the intermediate carrier 17 on the one hand and the gear 20 of the adjusting mechanism 19 on the other hand.

70

In machines doing this class of work it is quite important that the spaced rings—that is the ball raceways or seats upon these rings—be a uniform distance from the operative face of the abrading wheel 7. This 75 means that the segment rings 11 and 12 should be positioned with a nicety of adjustment. The carriers for these segment rings are preferably made of cast-iron and while it is possible to finish these carriers so 80 that when the machine is first assembled the segment rings will be properly positioned relative to the abrading wheels, still these carriers are liable to warp or change their shape in such manner as to destroy the adjustment required. This warping or distortion of the material in the carrier takes place as the iron "seasons". In order that this warping or distortion may be compensated for there are provided dutchmen D 85 and D' between the segment rings 11 and 12 and the corresponding inner and outer carriers for the rings. A dutchman construction such as is used is illustrated in Figs. 3 and 4. The dutchman is preferably in 90 the form of a continuous ring having therein openings 51 and 52 through which there pass screws or bolts 53 which clamp a segment ring to its carrier. Between the openings 51 and 52 there is also provided a 95 screw-threaded opening 54 in which there is an adjusting screw 55 that can be turned so as to adjust the position of the segment ring relative to the dutchman whereby the segment ring can be properly positioned with a nicety of adjustment relative to the operative surface of the abrading wheel. There may be several sets of these openings 100 51, 52 and 54 about the dutchman. If desired, instead of placing the screw-threaded opening 54 in a dutchman there could be provided a screw-threaded opening in the corresponding carrier for instance, whereby the dutchman could be positioned relative to the carrier with a nicety of adjustment 105 110 and in this way regulate the position of the corresponding segment ring relative to the abrading wheel. It will therefore be seen that dutchmen, such as D and D', can be employed where it is desired to obtain the 115 nicety of adjustment of the inner and outer segment rings 11 and 12 relative to the abrading wheel.

If the machine is to be employed for grinding balls of different sizes, that is 125 small sized balls at one time and large sized balls at another time, it has been found advisable to have possible different lateral adjustments between the position of the axis of the emery wheel on the one hand and the 130

center or axis of the spaced segment rings and the ball pressing ring on the other. This adjustment is desirable because in the feeding in of the smaller balls that portion of the outer edge of the emery wheel which is nearest to the feeding-in means should be farther to the left (see Fig. 2) than is the case when larger balls are being ground.

In the construction shown this lateral adjustment is taken care of by moving laterally the housing 3 in which there is carried the shaft 4 upon which the emery wheels are mounted. This lateral adjustment is enabled to be realized by means of the bolts 55 which pass through the slotted openings 56 that are in the housing 3 into the base or main frame 1 of the machine. When the bolts 55 are tightened the housing can be securely held in place in the required adjusted position on the main frame whereby the emery wheels will be properly positioned for balls of the particular size being ground. If desired, instead of having the housing 3 made adjustable the lateral adjustment could be taken care of by making the bearings for the shaft 4 laterally adjustable, or by constructing the machine so that the common carrier and the parts immediately associated therewith or carried thereby could be adjusted laterally relative to the main frame or what is the same thing, relative to the emery wheel.

It will be manifest that the invention can be embodied in the various forms and modifications without departing from the spirit and scope thereof.

What I claim and desire to secure by Letters Patent of the United States is:—

1. A ball grinding machine comprising in combination a main frame supporting thereupon shaft bearing members, a shaft in said bearing members and carrying a tubular abrading wheel, said frame also supporting thereupon a common carrier, which carrier is mounted on the main frame in a manner to permit of adjustment toward and from the abrading wheel, means extending between the frame and said carrier for forcing said carrier toward the abrading wheel, spaced supporting or segment rings on said carrier, a carrier which is revolvably mounted upon said common carrier and a ball-revolving ring or ball-pressing ring on said revoluble carrier.

2. A ball grinding machine of the class described comprising in combination a main frame, a main or driving shaft having at each end thereof heads to which there are secured abrading or grinding members, a main bearing member mounted upon said frame and carrying said shaft, at each end of the main frame an inner carrier and an outer carrier connected together and adjustable toward and from the abrading members, means between the frame and said car-

riers for effecting said adjustment, an intermediate carrier revolvably mounted upon said inner carrier, an inner segment ring or ball-supporting ring secured to said inner carrier, an outer segment ring or ball-supporting ring secured to said outer carrier, a ball-revolving ring or ball-pressing ring secured to said intermediate revoluble carrier, and means for adjusting the intermediate carrier along the inner carrier.

3. A ball grinding machine of the class described comprising in combination with a tubular abrading wheel of inner and outer spaced segment or ball-supporting rings, a ball-revolving ring or ball-pressing ring positioned on the opposite side of said segment rings from which the tubular abrading wheel is located, a carrier common to said inner and outer segment rings, an intermediate carrier for supporting said ball-revolving or ball-pressing ring, means between said intermediate carrier and said common carrier for adjusting the intermediate carrier relatively to said common carrier, and means for adjusting the common carrier and the parts carried thereby toward and from the abrading wheel.

4. A ball grinding machine of the class described comprising in combination with a tubular abrading wheel of inner and outer spaced segment or ball-supporting rings, a ball-revolving ring or ball-pressing ring positioned on the opposite side of said segment rings from which the tubular abrading wheel is located, a carrier common to said inner and outer segment rings, an intermediate carrier for supporting said ball-revolving or ball-pressing ring, means between said intermediate carrier and said common carrier for adjusting the intermediate carrier relatively to said common carrier, and means for adjusting the common carrier and the parts carried thereby toward and from the abrading wheel, the axis about which the abrading wheel rotates being offset with respect to the axis about which the ball-revolving ring rotates.

5. A ball grinding machine of the class described comprising in combination with a tubular abrading wheel of inner and outer spaced segment rings or ball-supporting rings, a ball-revolving ring or ball-pressing ring positioned on the opposite side of said segment rings from which the tubular abrading wheel is located, a carrier common to said inner and outer segment rings, means for moving said common carrier and the parts carried thereby toward and from said abrading-wheel, an intermediate carrier for supporting said ball-revolving or ball-pressing ring, and means between said intermediate carrier and said common carrier for adjusting the intermediate carrier relatively to said common carrier.

6. A ball grinding machine of the class

described comprising in combination with a tubular abrading wheel of inner and outer spaced segment rings or ball-supporting rings, a ball-revolving ring or ball-pressing ring positioned on the opposite side of said segment rings from which the tubular abrading wheel is located, a carrier common to said inner and outer segment rings, an intermediate carrier for supporting said ball-revolving or ball-pressing ring, and means between said intermediate carrier and said common carrier for adjusting the intermediate carrier relatively to said common carrier, there being spring means between 15 said ball-pressing ring and said intermediate carrier for yieldably forcing the pressing ring against the balls being ground.

7. A ball grinding machine of the class described comprising in combination with a tubular abrading wheel of inner and outer spaced segment rings or ball-supporting rings, a ball-revolving ring or ball-pressing ring positioned on the opposite side of said segment rings from which the tubular abrading wheel is located, a carrier common to 20 said inner and outer segment rings, an intermediate carrier for supporting said ball-revolving or ball-pressing ring, and means between said intermediate carrier and said common carrier for adjusting the intermediate carrier longitudinally relative to said common carrier, the axis of rotation of the abrading wheel being eccentric relative to the axis about which the ball-revolving ring 25 or ball-pressing ring rotates, which ring is concentric with the ball seats on the segment rings.

8. A ball grinding machine of the class described comprising in combination a tubular abrading wheel, a ball-revolving ring or ball-pressing ring, spaced ball-supporting rings or segment rings located between said abrading wheel and said ball-pressing ring, a common carrier for said segment rings, an 30 intermediate carrier for said ball-pressing ring, means for adjusting said ball-pressing ring relatively to said wheel, means for adjusting said common carrier relative to said wheel, the center of said segment rings being offset with respect to the axis of rotation of the abrading wheel whereby the entire operative surface of the abrading wheel will be utilized.

9. A ball grinding machine of the class described comprising in combination a tubular abrading wheel, a ball-revolving ring or ball-pressing ring, spaced ball-supporting rings or segment rings located between said abrading wheel and said ball-pressing ring, a common carrier for said segment rings, an intermediate carrier for said ball-pressing ring, means for adjusting said intermediate carrier along said common carrier, means for adjusting said common carrier relatively to 45 said wheel, the center of said segment rings

being off-set with respect to the axis of rotation of the abrading wheel whereby the entire operative surface of the abrading wheel will be utilized.

10. A ball grinding machine of the class described comprising in combination on a main frame, an abrading wheel carried on a shaft which is mounted in bearings on said main frame, spaced ball-supporting rings or segment rings opposite said abrading wheel, a ball-revolving ring or ball-pressing ring arranged to maintain balls when on said segment rings in operative engagement with said abrading wheel, an inner carrier for supporting the inner of said segment rings, 50 an outer carrier for supporting the outer of said segment rings, an intermediate revolvable carrier for said pressing ring which intermediate carrier is revolvably mounted on the inner carrier, a gear connected to said intermediate carrier, a gear on a shaft which is mounted on said outer carrier for transmitting power to said first-mentioned gear, and means for adjusting the intermediate carrier along said inner carrier. 90

11. A ball grinding machine of the class described comprising in combination a main frame, a tubular abrading wheel carried on a shaft which is mounted in bearings on said main frame, spaced ball-supporting rings or segment rings opposite said abrading wheel, a ball-revolving ring or ball-pressing ring arranged to maintain balls when on said segment rings in operative engagement with said abrading wheel, an inner carrier for supporting the inner of said segment rings, 95 an outer carrier for supporting the outer of said segment rings, an intermediate revolvable carrier for said pressing ring, which intermediate carrier is revolvably mounted on the inner carrier, a gear connected to said intermediate carrier for imparting rotary motion to said intermediate carrier, a gear on a shaft which is mounted on said outer carrier for transmitting power to said first-mentioned gear, and means for adjusting the intermediate carrier along said inner carrier, the axis of rotation of said tubular abrading wheel being at one side of the center of the segment rings whereby the entire operative 100 surface of said wheel can be utilized. 110

12. A ball grinding machine of the class described comprising in combination a tubular abrading wheel, inner and outer spaced segment rings, an inner carrier for said inner ring, an outer carrier for said outer ring, an intermediate carrier revolvably mounted on one of the carriers for said segment rings, means between said intermediate carrier and the carrier upon which it is 120 mounted whereby said intermediate carrier can be adjusted along the carrier upon which it is mounted, means for rotating said intermediate carrier, and means for adjusting the carriers of said segment rings toward 125 130

and from the abrading wheel, the construction being such that the centers of the segment rings and the axis about which the intermediate carrier rotates are eccentric 5 relative to the axis of rotation of the tubular abrading wheel, the arrangement being such that the entire surface of the abrading wheel will be utilized.

13. A ball grinding machine of the class 10 described comprising in combination a tubular abrading wheel, spaced ball-supporting rings, a rotating ball-pressing ring, means for feeding balls into operative position relative to said members and for conveying 15 balls from between said members, a carrier common to said segment or ball-supporting rings, a revolute intermediate carrier for said ball-pressing ring, means for adjusting said common carrier toward and from said 20 wheel, said feeding and conveying means being mounted upon and movable with said common carrier.

14. A machine of the class described comprising in combination a tubular abrading 25 wheel, spaced ball-supporting rings or segment rings opposed to said wheel, a carrier common to said segment rings, means for adjusting said carrier toward and from said abrading wheel, a pressing ring, an intermediate carrier therefor revolutely mounted 30 upon said common carrier, means for adjusting the position of said intermediate carrier along said common carrier, means on said common carrier for rotating said intermediate carrier, and means supported by said common carrier for directing balls to be ground into the space between said abrading 35 wheel and said pressing ring, for receiving balls from said space and for mixing the balls thus received prior to their reintroduction 40 into the same space.

15. A ball grinding machine of the class described comprising in combination an abrading wheel, ball-supporting rings, a 45 common carrier for the latter, a ball-revolving ring or ball-pressing ring, a revolute carrier therefor which revolute carrier is supported by a radial bearing on said common carrier, means between said common 50 carrier and said revolute carrier for rotating the latter, adjusting means between said revolute carrier and said common carrier which adjusting means comprises a gear having screw-threads in mesh with a screw-threaded portion of said common carrier whereby as said gear is rotated the revolute carrier will be adjusted along said common carrier, and a thrust bearing between said 55 gear and said revolute carrier.

16. In combination in a double-end ball 60 grinding machine of the class described two abrading wheels mounted and arranged so that the thrust of one abrading wheel is opposed by the thrust of the other abrading 65 wheel, and associated with each of the

abrading wheels the following: spaced segment rings, a common carrier for said rings, a ball-revolving ring, a revolute carrier for said ball-revolving ring, means for rotating said revolute carrier, means for positioning 70 said revolute carrier toward and from its corresponding abrading wheel and relative to its corresponding carrier, and means for adjusting the common carrier toward and from its corresponding abrading wheel. 75

17. A ball grinding machine of the class described comprising in combination a tubular abrading wheel, ball supporting rings, a rotating ball pressing ring, means for feeding balls into operative position relative to said rings and for conveying balls from between said rings, a carrier for said ball supporting rings, means for adjusting said carrier toward and from said abrading wheel, said feeding and conveying means being mounted upon and movable with said carrier. 80

18. In combination in a double-end ball grinding machine of the class described two abrading wheels mounted and arranged so that the thrust of one abrading wheel is opposed by the thrust of the other abrading wheel, and associated with each of the abrading wheels the following: ball supporting and guiding rings, a common carrier for 90 said rings, a ball-revolving ring, a revolute carrier for said ball-revolving ring, means for rotating said revolute carrier, means for positioning said revolute carrier along and relative to its corresponding common carrier, means for adjusting the common carrier toward and from its corresponding abrading wheel, mixing means, feeding means for conveying the balls to be operated upon from said mixing means into operative 95 position in respect to its corresponding abrading wheel, and conveying means for receiving balls from said operative position and conveying them to the mixing means. 100

19. In combination in a double-end ball grinding machine of the class described two abrading wheels mounted on a common shaft which shaft is mounted in radial bearings carried on a main frame and also provided with thrust bearings, and associated with each of the abrading wheels the following: spaced segment rings, a common carrier for said rings, a ball-revolving ring, a revolute carrier for said ball-revolving ring, means for rotating said revolute carrier, means for positioning 110 said revolute carrier toward and from its corresponding abrading wheel and relative to its corresponding carrier, means for adjusting the common carrier toward and from its corresponding abrading wheel, mixing means supported on each common carrier, feeding means for conveying the balls to be operated upon from said mixing means into operative position in respect to its corresponding abrading wheel, 115 120

wheel, mixing means supported on each common carrier, feeding means for conveying the balls to be operated upon from said mixing means into operative position in respect to its corresponding abrading wheel, 125 130

and conveying means for receiving balls from said operative position and conveying them to the mixing means, said feeding means and said conveying means being supported on said common carrier and movable therewith.

20. In combination with a ball grinding machine of the class described an abrading wheel, spaced segment rings in front of said abrading wheel, a common carrier for said rings, a ball-revolving ring, a revoluble carrier for said ball-revolving ring, springs between said revolving ring and said revoluble carrier whereby said revolving ring is yieldably mounted upon said revoluble carrier, means for rotating said revoluble carrier, means for positioning said revoluble carrier toward and from the abrading wheel and relative to its common carrier, and means for adjusting the common carrier toward and from its corresponding abrading wheel.

21. In combination with a ball grinding machine of the class described an abrading wheel, spaced segment rings in front of said abrading wheel, a common carrier for said rings, a ball-revolving ring, a revoluble carrier for said ball-revolving ring mounted upon said common carrier, springs between said revolving ring and said revoluble carrier whereby said revolving ring is yieldably mounted upon said revoluble carrier, means for rotating said revoluble carrier relatively to said common carrier, means for positioning said revoluble carrier toward and from the abrading wheel and along the common carrier, and means for adjusting the common carrier toward and from its corresponding abrading wheel.

22. A ball grinding machine of the class described comprising an abrading wheel arranged so that the thrust of one abrading wheel is opposed by the thrust of the other abrading wheel, a shaft common to said wheels, which shaft is mounted in radial bearings carried on a main frame and is also provided with thrust bearings between it and the main frame and in operative relation with each of the abrading wheels, a pair of spaced segment rings for each wheel, a common carrier for each pair of said rings, a ball-revolving ring associated with each abrading wheel, a revoluble carrier for each said ball-revolving ring, means for rotating said revoluble carrier, means for positioning said revoluble carrier toward and from the abrading wheel and relative to said common carrier, and means for adjusting the common carrier toward and from its corresponding abrading wheel.

23. A ball grinding machine of the class described comprising an abrading wheel arranged so that the thrust of one abrading wheel is opposed by the thrust of the other abrading wheel, a shaft common to said wheels, which shaft is mounted in radial

bearings carried on a main frame and is also provided with thrust bearings between it and the main frame and in operative relation with each of the abrading wheels, a pair of spaced segment rings for each wheel, a common carrier for each pair of said rings, a ball-revolving ring associated with each abrading wheel, a revoluble carrier for each ball-revolving ring, means for rotating said revoluble carrier, means for positioning said revoluble carrier toward and from the abrading wheel and relative to said common carrier, means for adjusting the common carrier toward and from its corresponding abrading wheel, mixing means, means for conveying the ball to be operated upon from said mixing means into operative position in respect to its companion abrading wheel, and means for receiving balls from said operative position and conveying them to the mixing means, said feeding means and said conveying means receiving support from said common carrier.

24. A ball grinding machine comprising in combination a rotating abrading wheel, spaced segment rings, carriers therefor, a rotating ball-revolving ring, there being a dutchman construction between each of said segment rings and its corresponding carrier.

25. In combination in a machine of the class described a segment ring, a carrier therefor and a dutchman construction between each of said segment rings and its carrier.

26. In combination in a machine of the class described a segment ring or ball-supporting ring, a carrier therefor and a dutchman in the form of a ring having openings through which there pass bolts that secure said segment ring to its carrier, there also being adjusting screws whereby said segment ring can be positioned relative to its carrier.

27. In combination a rotating abrading wheel, spaced ball-supporting rings, a yieldable ball-pressing ring, carriers for said ball-supporting rings, and a dutchman between each of said supporting rings and its carrier, said dutchman construction being provided with adjusting screws whereby said supporting rings can be positioned with respect to the wheel, said supporting rings being secured to said carriers by bolts which pass through the dutchman.

28. A ball grinding machine comprising in combination spaced segment rings, a ball-revolving ring for pressing balls against said segment rings, an emery or abrading wheel which revolves about an axis that is eccentric or off-set laterally with respect to the axis of the ball-revolving ring, means for feeding balls into the operating space between said emery wheel and said ball-revolving ring, and means whereby a lateral adjustment can be effected between said

emery wheel on the one hand and said spaced segment rings and ball-pressing ring on the other.

29. A machine of the class described comprising in combination spaced segment rings, a ball-pressing ring on one side of said segment rings, an abrading wheel on the other side of said spaced segment rings, means for feeding balls into position to be operated upon by said abrading wheel, and means whereby there can be effected a lateral adjustment between said abrading wheel and said spaced segment rings.

30. A machine of the class described comprising in combination spaced segment rings, an emery wheel at one side of said spaced segment rings, a ball-revolving ring at the other side of said spaced segment rings, means for feeding balls into position to be operated upon between said emery wheel and said ball-revolving ring, means whereby said emery wheel can be adjusted laterally, and means whereby said spaced

segment rings can be adjusted longitudinally.

31. A machine of the class described comprising in combination a laterally adjustable rotating emery wheel, a pair of ball-supporting rings and a ball-pressing ring.

32. A machine of the class described comprising in combination a rotating emery wheel, a ball-pressing ring having associated therewith spaced segment rings, means for feeding balls to said segment rings in position to be operated upon by said emery wheel while being pressed against the supporting rings by said pressing ring, and means whereby there can be effected a relative lateral adjustment between the feeding means and said emery wheel.

This specification signed and witnessed this 23d day of March A. D. 1917.

OTTO W. SCHAUM.
